UNITED STATES PATENT OFFICE.

UMBERTO MAGNI, OF SAN FRANCISCO, CALIFORNIA.

JAR-CLOSURE.

1,077,538.

Specification of Letters Patent.

Patented Nov. 4, 1913.

Application filed July 2, 1913. Serial No. 776,909.

To all whom it may concern:

Be it known that I, UMBERTO MAGNI, residing at San Francisco, in the county of San Francisco and State of California, 5 have invented a new and Improved Jar-Closure, of which the following is a specification.

My invention relates to jar closures and particularly to that type of closures in which the sealing member or gasket is held to its seat on the jar or bottle and confined against possible leakage by a sealing cap, and my invention primarily has for its object to provide an improved jar and closure 15 member therefor in which the several co-operating parts are so constructed and designed to coact in such a manner whereby the sealing gasket or member can be quickly and securely applied without the aid of a 20 special implement and whereby the same may be conveniently removed from the jar or bottle.

Another and important object of my invention is the provision of a closure means 25 of the general character stated, adapted for constant reuse and in which the sealing member or gasket is at all times contained within the cap and is thereby not separated from the cap when the closure is removed 30 from the jar and in which the cap of the closure member is so formed that a worn sealing member can be removed therefrom and a new sealing member may be substituted therefor.

35 My invention consists of the peculiar arrangement and construction of the parts hereinafter fully explained, specifically pointed out in the appended claim and illustrated in the accompanying drawing, 40 in which:

Figure 1 is a perspective view of a jar with my improvements applied. Fig. 2 is a similar view that illustrates the manner in which the cap and the sealing members 45 are removed from the jar. Fig. 3 is a transverse section of the upper end of the jar, and the closure devices, taken substantially on the line 2-2 on Fig. 1. Fig. 4 is a similar view that illustrates the first 50 position of the closure devices in fitting them over the jar. Fig. 5, the second position, the clamping fingers being shown as spread to pass over the lower or locking flange on the jar. Fig. 6 is a perspective 55 view of the closure cap and the sealing disk and gasket.

In carrying out my invention, the jar or bottle 1 has its upper or mouth end especially constructed for coöperating with my construction of closure device, and to such end the mouth of the jar has an annular rib 2 adjacent the opening 3 that rises up from and forms, as it were, a portion of the annular bearing or rim 4 upon which the sealing ring or gasket of the closure devices seats.

The outer edge of the rim or seat 4 is rounded and merges with an annular groove 5, the lower portion of which merges with a second annular flange 6 having a substantially undercut edge 60 that ends at the contracted or neck portion 7 of the jar body, as is clearly shown in Figs. 3, 4 and 5, by reference to which it will be also seen that the outer edge of the seat or rim 4 and the flange 6 are of different diameters, the reason for which will presently appear.

The closure device for my improved construction of jar, includes a gasket or sealing ring 8 of any suitable compressible material, a paraffin disk 9 on the under side of the ring and a like disk 10 on the upper side of such ring.

11 designates what I term the cap and locking member of the closure device, since it serves as a cap or cover for the jar mouth and the means for holding the washers and disks in an air-tight position over the jar mouth. The cap is formed of a resilient sheet metal and consists of the top or body portion, a pendent flange 12 that is cut out or scalloped to form a series of pendent members 13, the lower ends of which are bent inwardly on a slightly upward incline to form locking fingers 13a.

By reason of constructing the closure devices as stated when once slipped within the scalloped flange of the cap, the gasket and the paraffin disks cannot be dropped out of the cap when fitting the closure devices 100 either onto or off the jar, but they may be readily forcibly removed from the cap by buckling or bending up the gasket and the disks when it is desired to substitute new disks and gasket.

105 By forming the closure cap with a scalloped-like flange and terminating the ends of the "scallops" into inturned locking fingers, the cap with the sealing members can be almost instantly applied to the jar, 110 since in applying the cap, (see Fig. 4) the lower or finger edges of the "scallops" en-

gage the rounded outer edge of the upper or seat face of the jar and are thereby caused to spread, until they pass over the said rounded edge, after which the spring 5 of the scallop members causes their lower or finger ends to hug the annular depression in the jar below the said edge and thereby hold the cap true as it is further forced down to the second position (see Fig. 5) 10 at which time the sealing members will be in engagement with the top of the jar and locking finger just ready to slip over the outwardly curved undercut flange of the jar to become interlocked therewith to securely 15 hold the closure devices air-tight over the jar mouth.

It should be stated that in forming up the closure devices, particularly the cap, the pendent members with the interlocking or 20 indent portions and the lower or locking flange on the jar are relatively so proportioned that it will require some pressure to bring the locking fingers of the cap over the locking flange after the closure device 25 has gone down to the second position (Fig. 5).

To remove the cap it is only necessary to spring out the longer fingers from one side of the jar, after which the cap with the sealing members may be readily swung off (see arrow Y) the jar.

Although my construction of closure devices may be cheaply manufactured they may be reused a number of times and when 35 desired new gaskets substituted for the worn ones.

By forming the top rim of the jar next the opening with a raised annular rib, a supplemental means is provided for positively effecting an air-tight seal, since the 40 paraffin disk and the washer are caused to bite down over the rib when the cap is closed down.

Among other advantages, in the use of

my jar and closure therefor, is, that by reason of forming the jar body with an inwardly curved annular groove just above the locking flange thereof, the closure member, after the jar is filled with the contents to be cooked, can be applied and held to the 50 second position, that is with the locking fingers engaging the annular groove in the jar while the contents are being cooked,—the position of the cap allowing the sealing members to rise off their seat during the 55 cooking.

When thus positioned, after the contents have been cooked, all that is then necessary is to slap down on the cap to cause it to assume the final or locked position shown in 60 Fig. 3, it being obvious that when thus applied as the jar and the contents thereof cool, the vacuum created causes the closure devices to form a perfect sealing of the jar.

What I claim is:

As a new article of manufacture, a jar having a mouth and two distinct annular grooves on its outside adjacent to said mouth to form a shoulder portion at the intersection of such grooves, the under face 70 of said shoulder being straight cut, the first of said grooves being curved throughout in cross section and lying between the mouth end and the second groove, and a cap consisting of a body portion having a pendent 75 flange, and resilient gripping fingers adapted to rest in said grooves, the fingers supporting the body portion of the cap in a plane above the mouth of the jar when said fingers engage the first groove, and said 80 fingers holding the body portion of the cap in sealing position with the jar when said fingers engage in the second groove.

UMBERTO MAGNI.
